Attorney

UNITED STATES PATENT OFFICE

ANTHONY MONTALBANO, OF LOS ANGELES, CALIFORNIA

LIQUID DISPENSING CUP

Application filed September 29, 1931. Serial No. 565,788.

This invention relates to liquid dispensers and has for a particular object the provision of a container adapted, by virtue of a plurality of spaced relatively small discharge tubes, to evenly dispense and distribute a liquid over a given area.

In dispensing soaps and oils for scalp treatments and the like in barber and beauty shops, for instance, it has heretofore been customary to dispense such liquids from a bottle having a single discharge orifice, or by pouring the liquid from a cup over the hair and scalp. This practice is wasteful, inconvenient and unsanitary, for the reason that it is practically impossible to obtain an even and regulated discharge of the liquid; and furthermore because of the fact that by thus dispensing the liquid, it is merely poured over the hair and much of it flows off the hair without reaching the scalp. By providing a plurality of circumferentially spaced rigid and projecting discharge tubes of relatively small diameter in my device, the operator is enabled to obtain an even flow and distribution of the fluid in a number of relatively small streams, and by placing the discharge end of the tubes beneath the hair and directly over the scalp, the fluid is discharged directly onto the scalp surface. These accomplishments form the more particular objects of my invention.

While it will be obvious that my invention may assume various forms and be adapted to various uses, one form and adaptation which it may assume is that of such a shampoo soap dispenser, and I shall now describe and illustrate it in that particular adaptation, for which purpose I refer to the accompanying drawings, in which:

Fig. 1 is a perspective view of a dispenser embodying my invention;

Fig. 2 is a cross-section on line 2—2 of Fig. 1, and

Fig. 3 is a plan view of the device.

Referring now more particularly to the accompanying drawings, the numeral 10 designates the cup-shaped container body, which is preferably cylindrical with a closed bottom end 11 and has a flanged top portion 12 to prevent overflow of the contained liquid when the cup is tilted. I illustrate flange 12 as extending around the entire circumference of top portion of the cup as I find this structure to aid economy of manufacture, although it will be obvious that the flange may only extend around a portion of the cup top adjacent the dispensing tubes to be described. A filling opening 15 is provided in the top portion of the cup, which opening is offset from the center as shown to the side opposite the dispensing tubes.

Circumferentially spaced along the side walls of the container, near the top thereof, I provide a plurality of dispensing tubes 16, constructed of metal or some rigid material, through which the liquid is dispensed when the cup is tilted sufficiently for the contained fluid to pass through the tubes. These tubes project substantially horizontally beyond the outer surface of the side walls of the cup a distance of approximately one inch, although the length of these projections may be changed as desired. The provision of a multiplicity of tubes of small diameter so placed and spaced, enables the user to obtain an even flow and distribution of the fluid, in comparatively small individual streams, directly over the scalp. The number and spacing of the tubes are governed by the area over which the liquid is to be distributed in one operation or tilting of the cup. I have found a series of four such tubes, each having an inner diameter of about one-eighth of an inch and spaced about one-half inch apart to be preferable for ordinary use. By thus employing four individual spaced discharge tubes, each having a one-eighth inch diameter, I obtain, in one "pouring", an even distribution of liquid, which is much more efficient and sanitary than can be obtained by

the old method of pouring say a one-quarter inch stream in one spot over the hair. It is desirable to have the tubes project outwardly from the cup a sufficient distance to enable 5 the discharge ends of the tubes to be buried in the hair so that when the fluid is discharged it is discharged directly upon the scalp surface. Tubes 16 preferably have flanged inner ends 17 which are secured to the

10 inner surface of the cup wall at 18 as by soldering; the tubes projecting through holes 19 in the side walls of the cup. Obviously it is preferable to have the discharge ends of the tubes on a substantially even plane; thus,

15 when the tubes are mounted in a cylindrical body such as cup 10, it is necessary to have the two end tubes of slightly greater length than the two inner tubes, as best shown in Fig. 2.

20 A handle H is provided at the side of cup 10 in such relative position to the tubes as will enable the operator to pour liquid from the container through the tubes by merely turning the hand to the right.

25 From the foregoing description it will become apparent that my invention is adaptable to many other uses to equal advantage and I therefore wish it understood that I do not confine its scope to the hereinbefore described details. Rather it is to be restricted only as appears in the appended claims.

I claim:

1. A liquid container having side walls and a plurality of circumferentially spaced discharge tubes mounted in the side walls, said tubes communicating from the interior to the exterior of the container.

35 2. A liquid container having side walls and a plurality of circumferentially spaced discharge tubes mounted in the side walls and communicating from the interior to the exterior of the container, said tubes projecting beyond the exterior of the side walls.

40 3. A liquid container having side walls and a plurality of circumferentially spaced discharge tubes mounted in the side walls and communicating from the interior to the exterior of the container, said tubes projecting substantially horizontally beyond the exterior of the side walls.

45 4. A liquid container having substantially vertical side walls and a plurality of circumferentially spaced discharge tubes mounted in the side walls near the top thereof and communicating from the interior to the exterior of the container, said tubes projecting substantially horizontally beyond the exterior of the side walls.

55 60 5. A liquid dispenser comprising: a cup-shaped container member having near the top thereof a plurality of horizontally spaced rigid discharge tubes adapted to discharge liquid from the interior to the exterior of the container, said tubes projecting substantial-

ly horizontally beyond the exterior of the container.

6. A liquid dispenser comprising: a cup-shaped container having a partially closed top with a filling opening near the side, and a plurality of small dispensing tubes projecting substantially horizontally near the top, said tubes projecting a substantial distance from the container side and ending in a straight plane.

70 In witness that I claim the foregoing I have hereunto subscribed my name.

ANTHONY MONTALBANO.
